UNITED STATES PATENT OFFICE.

FREDERICK D. MONTGOMERY, OF CHICAGO, ILLINOIS.

METHOD OF PRODUCING COLOR-TYPE ENGRAVINGS.

1,027,142.

Specification of Letters Patent.

Patented May 21, 1912.

No Drawing.

Application filed January 11, 1909. Serial No. 471,674.

To all whom it may concern:

Be it known that I, FREDERICK D. MONTGOMERY, a citizen of the United States, residing at Chicago, in the county of Cook 5 and State of Illinois, have invented certain new and useful Improvements in Methods of Producing Color-Type Engravings, of which the following is a specification.

My invention relates to the economical 10 production of plates for the making of colortype engravings, and more particularly to an improved method of producing color-plates of larger size than the originals, from which enlarged color plates I am enabled 15 to obtain prints or pictures more accurately representing the original object in form and in color effect. This I accomplish by enlarging the original plates by the aid of 20 photography.

My invention effects a very considerable 25 saving in time and labor and secures a more brilliant color effect in the finished work, especially in the reproduction of textile fabrics, and a closer simulation of weaves and textures than can be obtained by the ordinary methods.

My invention may be applied to the making 30 of color-plates (for printing in two, three, or more colors for reproducing in natural colors photographic facsimiles of textile fabrics, especially for use as salesmen's cards, window hangers, posters for billboards, illustrated street-car signs, and may also be employed for producing colored 35 supplements for newspapers, and for advertisements of various kinds.

I will describe my new process as applied 40 to the reproduction of the pattern and color effects of textile fabrics so as to secure a large colortype engraving suitable for salesmen's cards or for advertisements, but it will be noted that this specific application of my 45 invention is illustrative only, and that the precise method employed would be varied to some extent when applied to other purposes.

I may premise that the originals of these color-plates may be produced by the ordinary process, which is as follows: The object 50 to be reproduced, say, a fabric such as a woven fabric, for example, a rug or carpet, is first photographed through colored screens which suppress or modify all of the primary colors except one and accentuate 55 this remaining primary color. This operation is repeated for each of the primary

colors, thus producing for three-color work for instance three negatives each having such part of the picture as is represented by its primary color. From these color- 60 filtered negatives positives are prepared, and from these positives half-tone screen negatives are made. These screen negatives are then transferred to copper-plates made sensitive to the light. These plates are then etched, and in this etching process acid is used to give to the plates the proper relief, and the etcher must of course attain the proper color values by accurately determining the exact size of the dot or line so as to 65 give the correct tint in the plate, and when the three plates are thus prepared the object may be reproduced therefrom in colors. Heretofore these plates have been made as 70 large as the desired picture, and because of the labor necessarily bestowed upon the plates by the etcher and finisher (the same surface frequently being worked over three or four times and proofs made each time to 75 observe the effect of the labor) the pictures have been small. I have discovered a method whereby these small color-plates 80 may be enlarged economically, meaning thereby at a cost of not to exceed one-tenth of the enlarged plate if produced by the 85 method now in general use, the enlarged plate being more perfect and thus enabling a closer simulation of the texture and coloring of the original than would be possible 90 if it were produced by the method now in general use.

In carrying out my method I take color-plates produced in the way above described or in any other method, of less size than the desired picture or illustration. These 95 original color-type plates may be prepared for photographing by filling the low parts with white material leaving the relief portions exposed and these prepared plates are then placed before the camera and enlargements thereof made by the ordinary wet-plate photographic method. The step of 100 photographically enlarging at this stage of the method is important in that it cures whatever defects there may be in the original color plates due to the hand work thereon. These negatives are then transferred to zinc or copper plates previously sensitized to light and etched for relief by the ordinary etching process. These enlarged 105 plates are then ready for proofing in the primary color without the necessity of fur-

ther labor or attention on the part of the etcher or finishing engraver. Or instead of filling the original plates and photographing the same, the impressions in black ink on smoothly coated paper may be made, one from each plate. These prints or impressions representing the various colors, may then be photographically enlarged to produce negatives which are then treated 10 as above described in connection with the use of the filled plate.

To describe the saving effected by this process, it may be stated that colortype illustrations for carpets, rugs, wall-paper, 15 and the like are usually of two sizes, first, the catalogue size, which averages say 3 $\frac{3}{8}$ "x4 $\frac{1}{2}$ ", and, secondly, salesmen's cards, which are about 9"x12", these cards being carried by the salesmen and used instead of 20 carrying samples of the goods. It is obvious that by the use of my process the labor of etching and finishing the original colortype plates is applied upon a surface

of about 15 sq. inches, while the enlarged plate contains 108 sq. inches, and by the 25 use of my process this large plate is made more perfect than could be done by the present methods of production, and at an enormous saving in cost.

I claim:-

The herein described method of producing colored pictures of multi-colored objects, which consists in producing a plurality of impression plates of the same object, each plate representing a primary color 35 of the object, manually finishing each plate, producing an enlarged printing plate from each of the finished plates by a photographic transfer process, and printing a multi-color picture by means of the enlarged 40 printing plates, substantially as described.

FREDERICK D. MONTGOMERY.
